FIG. 6.

INVENTOR.
Lawrence Bonell

UNITED STATES PATENT OFFICE.

LAWRENCE BONELL, OF CHICAGO, ILLINOIS.

SEWING-MACHINE.

1,147,479.

Specification of Letters Patent. Patented July 20, 1915.

Application filed December 4, 1913. Serial No. 804,779.

To all whom it may concern:

Be it known that I, LAWRENCE BONELL, a citizen of the United States, and a resident of the city of Chicago, county of Cook, and 5 State of Illinois, have invented certain new and useful Improvements in Sewing-Machines, of which the following is a specification.

My invention relates to bobbins, such as 10 are used in sewing machines, and especially in shoe stitching machines.

The object of my invention is the production of a bobbin and case therefor which will be so constructed as to admit of the 15 viewing of the thread contained on the bobbin without the necessity of removing the bobbin from its case.

A further object is the production of a bobbin and case which will be so marked or 20 graduated as to apprise the operator of the machine of the quantity of thread contained on the bobbin, and thus avoid the objectionable experience of running out of thread before the work at hand has been completed.

25 Other objects will appear hereinafter.

The invention consists in the combinations and arrangements of parts hereinafter described and claimed.

The invention will be best understood by 30 reference to the accompanying drawing forming a part of this specification, in which,

Figure 1 is a front elevation of a bobbin and case therefor embodying my invention, 35 Fig. 2 is a side elevation of Fig. 1, Fig. 3 is a partial sectional front elevation of the bobbin detached, Fig. 4 is a side elevation of Fig. 3, Fig. 5 is a side elevation of the bobbin case, and Fig. 6 is a front elevation of 40 Fig. 5.

The preferred form of construction as illustrated in the drawing comprises a bobbin and case which is designed to accommodate the stitching thread 7. The bobbin 45 case 8 is in general construction of conventional design, being cylindrical in form and open at one side so as to permit of the insertion of the bobbin 9 thereinto. Said bobbin is also in general construction of conventional design, being adapted to loosely or 50 rotatably rest in the case 8 when the device is in use. Said bobbin is, however, provided at one side with a radially extending slot or opening 10 and the corresponding side of the bobbin case is provided with a slot 11 which is adapted for registration

with the slot 10, as clearly shown in Fig. 2. With this arrangement, it will be seen that, the thread contained upon the bobbin may be viewed through the slots 10 and 11, when the latter are in registration, without the necessity of removing the bobbin from the case as is necessary at the present time when the operator desires to examine the bobbin in order to ascertain whether or not there 65 is any thread contained thereon.

Provided upon the outer side of the bobbin adjacent the slot 10 thereof are graduations, as clearly shown in Figs. 2 and 4, which are indicative of certain amounts 70 of thread contained on the bobbin. For instance, the innermost graduation which is designated by the reference character 2, as shown, is so positioned that when the thread upon the bobbin is in registration therewith, as shown in Fig. 2 it will serve to apprise 75 the operator that the bobbin contains only enough thread for two pairs of shoes. Likewise the other graduations which are spaced along the opposite edges of the slot 10 serve 80 to indicate amounts of thread sufficient for five, six and seven shoes respectively, as will be readily understood. With this arrangement then, it will be seen that the operator will at all times be apprised of the quantity 85 of thread upon the bobbin in terms of the work upon which the thread is used, and thus avoid the objectionable experience of the thread running out before the work at 90 hand is completed.

The changing of bobbins in order to supply more thread when the thread has run out of the bobbin in use, necessitates a break in the work, and generally results in the production of a piece of work which is not 95 up to standard and therefore objectionable. With the present construction this, of course, will be overcome since if indications upon the bobbin show that there is not enough thread to completely finish the work 100 at hand, as for instance a shoe or a pair of shoes, the bobbin will be removed and a fresh one arranged in its place. The changing of bobbins in the middle of a job, that is before the work is completed, especially 105 in shoe stitching, necessitates a considerable waste of time which is not experienced where a bobbin is changed before the work is started, and it is contended that, with the present construction, this waste of time will 110 be obviated.

While I have illustrated and described the

2
preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.

- 10 Having described my invention what I claim as new and desire to secure by Letters Patent is:

Copies of this patent may be obtained for five cents each, by addressing the "Commissioner of Patents, Washington, D. C."

The combination of a sewing machine bobbin and a case for said bobbin, said bobbin and case having registrable openings 15 through which the thread contained on said bobbin may be viewed without the necessity of removing the bobbin from its case, substantially as described.

LAWRENCE BONELL.
